[57] CLAIM

The ornamental design for a transducer housing assembly for monitoring blood pressure and the like, as shown.

DESCRIPTION

FIG. 1 is a top plan view of a transducer housing assembly for monitoring blood pressure and the like showing our new design;

FIG. 2 is an elevational view of one end thereof;

FIG. 3 is an elevational view of the opposite end thereof;

FIG. 4 is a bottom plan view thereof;

FIG. 5 is an elevational view of one side thereof; and

FIG. 6 is an elevational view of the opposite side thereof.
